INC., OF BOSTON, MASSACHUSETTS, A CORPORATION OF MASSACHUSETTS

COMBINATION SCHOOL DESK AND SEAT STANDARD

Application filed August 6, 1925. Serial No. 48,495.

The invention to be hereinafter described relates to improvements in standards for school furniture and the like.

One of the purposes of the invention is to provide a standard which may be died out of and pressed from sheet steel with economy of material. Another purpose of the invention is to provide simple and efficient hinge means for the seat receiving arms.

10 The character of the invention may be best understood by reference to the following description of one good form thereof shown in the accompanying drawings, wherein:

15 Fig. 1 is a side elevation of a combination desk and seat construction embodying the invention;

Fig. 2 on an enlarged scale is a horizontal section taken on line 2—2 of Fig. 1;

20 Fig. 3 on an enlarged scale is a vertical section taken on line 3—3 of Fig. 1;

Fig. 4 on an enlarged scale is a perspective view of one of the seat supporting arms;

25 Fig. 5 is a perspective view of a portion of the filler;

Fig. 6 is an end view of the seat illustrating the means for securing the seat to the arms;

Fig. 6^a is a horizontal section taken on line 6^a—6^a of Fig. 1; and

30 Figs. 7 to 19 are views illustrating steps in the manufacture of the standards.

Referring to the drawings, the combination desk and seat construction shown therein comprises a desk 1 which is supported on and secured to the upper ends of a pair of standards 5. Each of these standards is died out of and pressed from sheet steel or other metal as more fully hereinafter described. Each standard has arms 7 and divergent legs 9 which are curved outward to give them the proper spread. The arms and legs are formed with flanges to stiffen the same. Located intermediately of the arms and legs is a body 11 which is of channel form and has a depressed panel 13 for ornamental and strengthening effect.

40 Fitted into the body of the standard and forming a part of the body is a filler 15 of channel form and having flanges 17 which 50 may be riveted or otherwise secured to the flanges of the body.

The seat back 19 may be secured to the front sides of the standards by fins 20 (Fig. 6^a) which enter a pair of oppositely inclined kerfs cut into the rear side of the back and oblique to the plane of the back, thereby to hold the back to the standards and prevent the same from moving laterally with respect thereto.

55 A pair of seat supporting arms 21 are died out of and formed of sheet steel and have depressed panels 23 for ornamental effect. At the upper edges of the arms are flanges 25 to contribute to the stiffness of the arms, and projecting obliquely from the flanges 25 are fins 27 adapted to enter a pair of oppositely inclined kerfs 29 cut into the under side of the wooden seat 31 and oblique to the plane of the seat. The construction is such that the seat may be presented to the arms and slid along the flanges thereof, so that the fins 27 will slide into the kerfs 29 and thereby hold the wooden seat down onto the arms and prevent the same from moving laterally with respect thereto. After the seat has been slid in place, a pair of screws 33 may be entered through the arm flanges 25 and into the wooden seat, thereby to prevent the latter from shifting longitudinally of the arms.

60 Each of the arms has a shoulder 35 which preferably is formed of sheet steel and integral with the arm 21. The shoulder has a web and marginal strengthening flange 37 which is a continuation of the arm flange 25. To further contribute to the strength of the arm, it may have an inwardly projecting bottom flange 39. Each of the arms provided with the panel or web 23 and flanges 25 and 39 is channel-shaped in cross-section. Since the fin 27 projects from the edge of the flange 25, and the arm is formed of sheet steel, the flange and fin have an inherent resilience which contributes to tight fit of the fins in the kerfs in the seat.

65 It is not always possible to cut kerfs in the seat of the same width as the fins, but by relatively springing the arms, the inherent resilience of the fins may be taken advantage of, and the fins may be placed under tension so that they will press tightly against walls of the kerfs. Similarly by relatively springing 70 the standards the fins on the front flanges

thereof may be placed under tension so that they will press tightly against walls of the kerfs in the seat back. The standards will be maintained in the positions to which they are sprung by being secured to the desk body 1.

The shoulder 35 overlaps the body 11 and has a cup 41 formed in the web thereof, and registering or mating with a cup 43 formed in the web of the filler 15 referred to. A bolt 10 projects through registering holes in the cups 41 and 43. Interposed between the cups is a cup-shaped brass washer 47, and interposed between the cup 41 and the nut of the bolt is a brass washer 49. These brass washers serve to prevent squeaking when the arms are rocked to raise and lower the seat.

A leaf spring 51 is confined between the head of the bolt and the inner face of the filler 15, thereby to exert a pressure for causing the bolt to grip the cups 41 and 43 between the head and nut of the bolt with sufficient friction to hold the arms and the seat in positions of adjustment. The shank of the bolt is flattened and projects through elongated 25 holes in the spring, the filler cup 43 and the brass washers, so as to prevent turning of the bolt and loosening of its nut. The hole in the cup 41 is somewhat larger than the shank of the bolt to allow enough clearance 30 to permit rocking of the arm.

To limit the rocking movements of the arm, it is formed to provide an arcuate groove 53 which is struck from the center of the bolt hole in the cup 41. A stop in the form of a 35 collar 55 is pressed from the web of the filler 15, and enters the arcuate groove 53. A leather washer 56 is on the collar 55. The construction is such that when the arm is rocked the groove will slide along the stop, and when the ends of the groove come into engagement with the stop, the rocking movements of the arm will be limited. The arm is formed with a reverse bend at the shoulder 40 to provide a recess for receiving the lower portion of the seat back when the arm is in up-tilted position.

The lower ends of the legs 9 are pressed to provide feet 57 which are cupped somewhat and have narrow outstanding flanges 59 to enable the feet to have proper engagement with the floor. Holes 61 in the feet are adapted to receive screws for securing the feet to the floor.

The front side of the standard has a smooth desirable appearance and conceals the hinge means for pivotally connecting the arm with the body of the standard and the means for limiting the rocking movements of the arm. 55 The hinge means and the limiting means are located at the rear of the back of the seat where they cannot come in contact with the hands or clothes of the person occupying the seat. The construction of the hinge means and limiting means is such that the parts

thereof are substantially enclosed and protected.

An important feature of the invention is the method practiced in the manufacture of the standard from metal strip stock of substantially uniform width. This method is illustrated in Figs. 7 to 19 inclusive, and comprises the following steps:

A die 63 (Fig. 7) has a fin 65 for cutting the slot 67 to provide the legs of the unit, and the die has a fin 69 to cut out the slot 71 to provide the arms of the unit. The die is brought down to cut at intervals strip stock 73 of steel or other suitable metal, and in so doing forms the end portion of one unit and the end portion of the next adjacent unit. Then the unit is pressed to form the flange 75 (Fig. 8) extending along one of the legs and one of the arms, and in the same operation the foot 77 is formed. Then by a similar operation the unit is pressed to form the opposite flange 79 extending along the other arm and the other leg, and in this same operation the foot 81 is formed.

Next are formed the panel 83 (Fig. 9) in the portion of the unit intermediate the slots 65 and 71, the panel 85 extending along the margins of the legs, and the panel 87 extending along the margins of the arms.

Then the unit is pressed to bend the leg 89 (Fig. 12) away from the other leg 91, and then with a differently shaped die the leg 91 is bent with a curvature away from the leg 89 so that it assumes the form in Fig. 13. One of the arms 92 is bent with a curvature away from the other arm.

Then the feet are trimmed and changed from the form indicated by the dotted line 93 in Fig. 17 to the form indicated by the full line 95 in said figure. Then the feet are pressed to provide the flange 97 (Figs. 18 and 19) and the countersunk portions 99 which are pierced to provide the holes 101 through which the nails or screws are inserted for securing the feet to the floor. Then the end 103 of one of the arms of the standard is bent so that it changes from the form shown in Fig. 13 to the form shown in Fig. 16.

The last step is the bending of the margin of the unit to provide the fin 105 (Figs. 14 and 15) adapted to enter a kerf in the back of the seat for securing the seat to the standard.

In thus forming the standard from a narrow strip of metal, very little stock is wasted. The legs and arms are formed with the required spread, but by the use of stock of uniform width throughout the length thereof. This saving of material is an important economy in the manufacture of these standards. If stock were required of a width equal to the distance between the tips of the feet, it will be readily apparent that there would be great waste of material.

It will be noted that the flanges 75 and 79 are tapered with their greatest width at their

feet. This enables each foot to be formed with a lateral inwardly extending portion (Fig. 19) of substantial length and enables the screw holes 101 in each foot to be located a sufficient distance apart so that when the feet are screwed to the floor lateral tilt of the standard will be effectively resisted.

By this method a single piece of sheet metal may be formed to provide a channel-shaped body, angle-shaped divergent legs projecting therefrom with feet at the lower ends thereof, a portion above the body for supporting a desk, and a member for receiving a seat back, the body being of sufficient area and form to cover the hinged portion or shoulder of the seat arm. The standard is not only strong and durable in construction, but also has a desirable ornamental design.

It will be understood that the invention is not limited to the specific embodiment shown, and that various deviations may be made therefrom without departing from the spirit and scope of the appended claims.

What is claimed is:

1. In a standard, a single piece of sheet metal formed to provide a channel-shaped body, angle-shaped legs projecting down from the body and having flanges in the plane of the back of the body, and other flanges perpendicular to said plane and longitudinally tapered so that the lower portions of said perpendicular flanges are materially wider than the upper portions of said flanges, and feet pressed from the lower end portions of the flanges of said legs and of substantial width for resisting lateral tilting of the standard.

2. In a standard, a single piece of sheet metal formed to provide a channel-shaped body, angle-shaped legs projecting from the body, and feet at the ends of said legs having a spread substantially greater than the width of the channel-shaped body; a channel-shaped filler secured to said body, an arm having a portion for supporting the seat and a portion overlapping the body and filler, and hinge means for the arm including mating cups and a bolt projecting through said cups.

3. In a standard, a single piece of sheet metal formed to provide a body, angle-shaped divergent legs projecting from the body, a member for receiving a seat back and a portion for supporting a desk; an arm formed of sheet metal having a seat supporting portion, and a portion overlapping the body, and means connecting the arm to the body including hinge means located at the rear of the seat back receiving member, said arm being formed to provide a recess for receiving the lower portion of the seat back when the arm is in up-tilted position.

4. A sheet metal standard comprising a channel-shaped body, angle-shaped legs projecting down from the body and diverging with a spread greater than the width of the body, a channel-shaped filler having flanges

secured to the flanges of the channel-shaped body, an arm for supporting a seat, and means including a hinge connecting the arm with the filler.
